UNITED STATES PATENT OFFICE.

GERALD W. HART, OF KANSAS CITY, MISSOURI, ASSIGNOR OF ONE-HALF TO
GEORGE S. HEGEMAN, OF SAME PLACE.

ELECTRIC SNAP-SWITCH.

SPECIFICATION forming part of Letters Patent No. 447,728, dated March 3, 1891.

Application filed August 21, 1890. Serial No. 362,648. (No model.)

To all whom it may concern:

Be it known that I, GERALD W. HART, a citizen of the United States, residing at Kansas City, in the county of Jackson and State 5 of Missouri, have invented certain new and useful Improvements in Electric Snap-Switches, of which the following is a specification.

My invention relates to improvements in 10 electric snap-switches; and the object of my improvement is simplicity of construction and general efficiency.

In the accompanying drawings, Figure 1 is 15 a plan view of my switch with the cap-plate and thumb-turn removed. Fig. 2 is a side elevation of my switch with the cap in vertical section. Fig. 3 is an enlarged vertical section on the line *x x* of Fig. 1 of a portion of the base, the cam-plate and switch-plate, the other 20 parts being shown in side elevation. Fig. 4 is an enlarged plan view of the switch-plate; Fig. 5, an enlarged plan view of the cam-plate; Fig. 6, an enlarged reverse plan view 25 of the spring-plate and spring. Fig. 7 is an enlarged horizontal section on a line below the spring-plate and above the spring, the cams of the cam-plate underneath being indicated by broken lines; and Fig. 8 is a like view of the same, with the spring moved into 30 the position where it is just ready to pass the point of one cam.

A designates the base, and B the cap, which conceals and protects the working parts of the switch with the exception of the thumb-turn *a*. 35 *b b* designate the contact-plates secured to the base A and provided with contact-pieces or brushes 9 and screws 10 for the attachment of the wires 11 11, between which the connections are to be made or broken.

40 12 designates a cam-plate having a hub 13 in its center, which forms a bearing for the shaft 14, to which the thumb-turn *a* is secured. The upper part of the cam-plate 12 is chamfered, so as to form four cams 15, the point 45 of each cam being followed by a let-off or incline 16, as shown most clearly in Fig. 5. The spring-plate *c* is rigidly secured to the shaft 14 near its upper end, so as to rotate therewith. Said plate is slotted obliquely, as 50 at 17, and provided on its upper side with a lever or link 18, pivoted to said plate by the pin 19. The opposite end of said link is provided with a swinging stud 20, which passes through the slot 17 downwardly to a point inside the cam-plate, where its end is preferably provided with a friction-roller 21, although, if desired, it may have direct contact with said cam-plate. The spring-plate is provided with a stud or pin 22, fixed to said plate, and any suitable spring, preferably a leaf-spring 23, is arranged on the studs or pins 20 and 22 with a constant tendency to force said studs apart. 55

Interposed between the cam-plate and the spring-plate and its spring is the switch-plate *d*. This plate is loosely mounted on the shaft 14, so as to turn freely thereon, while it is centered and held in position by said shaft, the shaft being shouldered just above said plate. The switch-plate *d* is provided with a slot 24, whose slant or incline is substantially the same as that of the cams 15 and transversely to that of the let-off or incline 16 of the cam-plate. The slot in the spring-plate is transversely to that in the switch-plate, and 70 substantially coincides with the let-off or inclines 16 of the cam-plate. The swinging stud 20 on the link of the spring-plate passes through said slot 24. The switch-plate is provided with contacts 25 at its opposite ends 75 for engaging the contact-pieces or brushes 9. The thumb-turn, for convenience of application, may be fitted to the shaft 14 by means of an internally-threaded hub and screwed upon the end of said shaft. Upon turning the 80 shaft through the thumb-turn the spring-plate moves with it, thereby partially revolving the entire spring. As the spring-plate and spring thus move along, the swinging stud rides up the edge of one of the cams, 85 moving the stud inwardly in the slots of the spring-plate and switch-plate. The switch-plate remains stationary until the lower end of the swinging stud passes the point of the cam. Fig. 8 illustrates the switch when this stud is 90 nearly ready to pass the point of one cam. As soon as the stud passes the point of the cam, the tendency of the spring to move the studs 20 and 22 apart moves the swinging stud 95 rapidly along the let-off or incline 16 into the 100

notch or recess formed by the junction of said incline and the next succeeding cam, the position of the parts at this time being indicated by the broken lines in Fig. 8. As soon as the 5 swinging stud 20 snaps down the incline or let-off, its motion is transversely to the slot in the switch-plate, and consequently it carries the switch-plate with it as it thus snaps off the point of the cam. There being four cams, 10 the switch-plate stops after having made a quarter-revolution, and if the motion of the shaft is continued to carry the roller and stud 20 by the next succeeding cam the switch-plate will be moved another quarter-revolution, 15 and so on repeatedly whenever the shaft is turned, thus closing or opening the circuit, as may be desired, by stopping the switch-plate when its contact-pieces are in or out of contact with the contact-pieces or brushes 9.

20 I claim as my invention—

1. The combination of the cam-plate having cams 15 and let-offs or inclines 16 with the

slotted switch-plate, spring-plate, the spring, and the stud 20, carried by said spring-plate and engaging said switch-plate and cams, substantially as described, and for the purpose specified.

2. The combination of the shaft, the spring-plate mounted to revolve with the same and slotted, as described, the stud or pin 22, fixed 30 on said spring-plate for one end of the spring, and the pivoted link carried by said spring-plate, a swinging stud at the outer end of said link, a spring connected to said studs with a constant tendency to force them apart, the 35 slotted switch-plate having the swinging stud extended through its slot, and the cam-plate for engaging the lower end of said swinging stud, substantially as described, and for the purpose specified.

GERALD W. HART.
